ADJUSTABLE HEAD FOR GOLF CLUBS

Joseph Verderber, Cleveland, Ohio

Application May 13, 1947, Serial No. 747,673

7 Claims. (Cl. 273—79)

1

This invention relates to golf clubs and more particularly to golf clubs of the type wherein the head may be adjusted to provide a variety of angles of approach to the golf ball.

During the course of the golf game, from driving tee to putting green, the player encounters a variety of terrain and distance. In order to play his shots correctly and meet the varying requirements of terrain and distance, the golfer, in each instance, must select a golf club having the proper loft or angle of approach, with respect to the golf ball.

It is customary for players to carry from ten to fourteen clubs of varying degrees of loft in order to accomplish the foregoing. This large number of clubs involves a substantial expenditure of money which often discourages prospective golfers from participation in the sport. The clubs are also a heavy burden making them inconvenient and tiresome to carry.

By making the head of the golf club adjustable to different angles of loft, the player needs only one club and thus is relieved of the expense and burden connected with the use of ten or more clubs.

It is a primary object of my invention to provide a golf club having a head which is adjustable to a variety of angles.

Another object of my invention is to provide an adjustable head for golf clubs which may be adjusted without the use of tools or implements.

Still another object of my invention is to provide an adjustable head for golf clubs which is rigidly and firmly maintained in any selected angle of loft.

A further object of my invention is to provide new and novel means of adjustment which are of rugged and simple construction.

A still further object of my invention is to provide an adjustable head for golf clubs which will enable the player to quickly select and adjust the head to the proper angle.

Other objects and advantages of my invention will become apparent during the course of the following description and with reference to the annexed drawings, forming a part thereof, in which like numbers designate like parts throughout the same.

In the drawings:

Fig. 1 is a side elevation of the head of a golf club embodying my invention.

Fig. 2 is an end elevation of the head of a golf club embodying my invention.

Fig. 3 is a view partly in section and partly in elevation, taken on line 3—3 of Fig. 1.

2

Fig. 4 is a fragmentary view taken on line 4—4 of Fig. 1.

Fig. 5 is a view partly in section and partly in elevation, taken on line 5—5 of Fig. 4, and showing details of the knob assembly.

Fig. 6 is a view partly in section and partly in elevation, taken on line 6—6 of Fig. 1.

Fig. 7 is an exploded view, partly in section and partly in elevation, of the parts comprising my invention.

Fig. 8 is a cross-sectional view taken on line 8—8 of Fig. 7.

Fig. 9 is a view taken on line 9—9 of Fig. 7.

Fig. 10 is a view taken on line 10—10 of Fig. 7.

Fig. 11 is a cross-sectional view taken on line 11—11 of Fig. 7.

Fig. 12 is a side elevation of the head of a golf club embodying a modified form of my invention.

Fig. 13 is an end elevation of the head of a golf club embodying the modified form of my invention.

Fig. 14 is a view, partly in section and partly in elevation, taken on line 14—14 of Fig. 12.

Fig. 15 is a sectional view taken on line 15—15 of Fig. 12.

Fig. 16 is a sectional view taken on line 16—16 of Fig. 12.

Referring now to Figs. 1 through 11, the upper

extremity of the hosel 1 of a golf club engages a shaft of conventional design (not shown). The other end of the hosel 1 is elbowed as at 2 and has an extension or spindle 3 having a machined external thread 4 thereon. The nature of the

thread 4 is of particular importance in my invention, it being required that the thread 4 have a helix angle sufficiently great so as to permit the spindle to turn when an axial component of force is applied to it. In order to obtain the effect

hereinafter described, the helix angle should be in excess of ten degrees. As drawn in Fig. 3, the thread 4 has a pitch of $1/18$ inch and a lead of $1/3$ inch, being three threads per inch, sextuple.

The spindle 3 is undercut along a portion of its length and machined to provide a nine-sided section 5 on the spindle.

The head 6 has a cavity or bore 7 which is internally threaded, as at 8, for a portion of its length to accommodate the sextuple thread 4 of the spindle 3.

Another portion of the bore 7 is threaded, as at 9, to accommodate the screw 10.

The screw 10 has an external thread 11, which has the same pitch as thread 4, but which is only a single thread and therefore has a lead of $1/18$

inch which is equivalent to $\frac{1}{6}$ of the lead of thread 4. In contradistinction to thread 4, the thread 11 is a left-hand thread.

The screw 10 has a cylindrical extension 12, which projects into the cavity 13 provided in the spindle 3. The extension 12 serves to support the washers 14 which are interposed between the spindle 3 and the screw 10. The opposite end of the screw 10 terminates in an extension 15 of square cross-section which projects into and is engaged by a cavity 16 of like cross-section, in the knob 17.

The knob 17 has an annular groove 18, the sides of which are substantially engaged by the point 19 of the set screw 20 which is threaded through the head 6 and bushing 21 through tapped openings 22 and 23 respectively. This construction prevents axial movement of the knob 17.

The bushing 21 has a cavity 24 retaining a spring 25. The spring 25 serves to press a ball 26 into engagement with depressions 27 on the knob 17, thus operating as a detent and giving tactile indication of proper positioning of the knob. As seen in Fig. 4, suitable indicia are inscribed on the face 28 of the knob 17, which correspond in number and spacing to the depressions 27, and which serve to indicate to the golfer the comparative angle of loft of the golf head.

A pin 29, blocking the groove 18, serves to restrict rotation of knob 17 to less than one revolution.

A set screw 30 is threaded into the head 6 through the opening 31 and engages one or another of the flat faces of the section 5 when the adjustment of the head is completed.

A cavity 32 is provided in the head 6 which may be filled with lead or other suitable material in order to permit the golfer to weight the club head to his individual liking.

The operation of the parts will now be described briefly.

The spindle 3 and the screw 10 are threaded into the bore 7 of the head 6 so as to tightly engage the interposed washers 14. Assuming the head 6 to be in the position indicated in solid lines in Fig. 2, the set screw 30 will be tightened so as to engage a flat face of the nonagonal section 5 of spindle 3. The golf club is now ready for use as a driver or number one iron. The impact of the face 33 of the head 6 with the golf ball will have a tendency to rotate the head 6 so as to cause a tightening relationship between the adjacent ends of spindle 3 and screw 10. Inasmuch as the screw 10 and spindle are already in tight engagement, as previously stated, the head 6 will maintain its position rigidly relative to the hosel 1, and the engagement of the set screw 30 with section 5 will prevent any tendency of the head 6 to rotate in a direction opposite to that induced by impact with the golf ball, such as might occur on the back or return swing of the club head.

Assuming now that the golfer desires to use the golf club as a number five iron, he will loosen the set screw 30 and rotate the knob 17, as shown in Fig. 4, in a counter-clockwise direction, until the character 5 on the face 28 of the knob occupies the position shown on the drawing by the character 1. Rotation of the knob 17 will be transmitted to screw 10 by means of the square extension 15. If the head 6 is held while the knob is turned, the spindle 3 will be moved slightly out of the bore 7 by the force exerted on the washers 14 by the screw 10. While being displaced longitudinally, the spindle 3 will be rotated in a counter-clockwise direction, as viewed in Fig. 2, and the club

head 6 will then be disposed at an angle to the longitudinal axis of the hosel and shaft. Conversely, if the shaft or hosel were held while knob 17 is rotated, the head 6 would rotate in the same direction as the knob, and occupy the position indicated in dotted lines in Fig. 2.

Due to the differential in lead between the left hand thread 11 on screw 10 and the right hand thread 4 on spindle 3, the head 6 will have an angular rotation of only one-sixth the angular rotation of the knob 17.

When the head has been thus adjusted, the set screw 30 is again tightened and the club is ready for play.

Although the thread 11 on screw 10 has been described as a left hand thread and the thread 4 on the spindle 3 has been described as a right hand thread it will be readily apparent that the thread 11 could be right hand and the thread 4 could be left hand, and the principle of operation of my invention will still be retained.

In order to return the head from the number 5 position to the number 1 position, the set screw 30 is loosened, the knob 17 rotated in a clockwise direction, the head similarly rotated, and the set screw 30 again tightened.

The knob 17 is limited in rotation to eight-ninths of a revolution or 320° by the pin 29, and therefore upon maximum rotation of the knob, the head 6 will have one-sixth the rotation or approximately 54° .

Thus it is apparent that the golfer may so adjust the head of his golf club as to make it the equivalent of any one of eight clubs having varying degrees of loft. It will further be noted that the adjustment can be quickly and easily made without the use of tools and that the novel construction embodied in my invention is such as to maintain the head firmly and rigidly in any one of the selected positions of adjustment.

Referring now to Figs. 12 through 16, I have shown a modified form of my invention employing a ball and race construction on the spindle 3 instead of machined threads.

In the modified form, a tapped cavity 34 is provided in the screw 10' which is adapted to receive the hollow head screw 35.

Grooves or races 36 are provided on the spindle 3', and like races 37 are provided internally of the bore 7' of the head 6'. In combination with the balls 38, the races are the equivalent of three threads per inch, quadruple, having a pitch of $\frac{1}{12}$ inch and a lead of $\frac{1}{6}$ inch.

The washers 14 are carried by the screw 35 and are maintained in spaced relationship by balls 39.

In assembly, the screw 35 is tightened so as to bear firmly against the shoulder provided therefor in the bore 13' of the spindle 3'. The screw 35 thus holds the spindle 3', the screw 10' and the interposed washers 14 and balls 39 in rigid juxtaposition each to the other. Therefore the longitudinal displacement of the spindle 3', and necessarily its angular rotation, is limited by the head of the screw 35, which, in turn, moves longitudinally in response to rotation of the screw 10'.

The principle of operation of the modified form of my invention is identical to that of the previously described form. The threaded members 10' and 3' which are of opposite inclination, serve to lock the head 6' against rotation in a counter-clockwise direction (as seen in Fig. 13) upon impact of the face 33' with the golf ball, and the screw 35 serves to prevent rotation of the head 6' upon the back swing of the club, thereby having a function which in part is similar to that per-

formed by the screw 30 in the first-described form of the invention. Due to the use of the balls 38 and 39, the frictional resistance between the operating parts is decreased and any required adjustments are easily and quickly made.

With reference now to the head 6 as seen in Fig. 2 and the head 6' as seen in Fig. 13, it will be noted that the heads are so designed and constructed that the mass of the head is preponderantly in the lower portion of the head rather than being distributed so as to be preponderantly behind the center of the face 33 or 33'. Inasmuch as the golf ball generally receives its impact from the lower portion of the club head, the aforementioned weight distribution utilizes the momentum of the club head to greatest advantage at the point of impact.

It will be understood that various changes may be made in the construction, shape, size and arrangement of the parts without departing from the spirit of my invention or the scope of the subjoined claims.

I claim:

1. In an adjustable head for a golf club, the combination of a head having a threaded cavity therein, the threads in one longitudinal portion of said cavity having a greater lead than the threads in the remaining portion of said cavity, a hosel having an integral extension forming a spindle threadedly engaging said first named portion of said cavity, said spindle being rotatable relatively to said head in response to an axial force applied thereto, and an element threadedly engaging said second named portion of said cavity in longitudinal abutment with said spindle, whereby rotation of said element relatively to said head causes proportional rotation of said spindle.

2. In an adjustable head for a golf club, the combination of a head having a threaded cavity therein, the threads in one portion of said cavity being of greater lead than the threads in the other portion of said cavity, a hosel having an integral extension forming a spindle threadedly engaging said first-named portion of said cavity, said spindle being rotatable in response to an axial force applied thereto, and an element threadedly engaging said second-named portion of said cavity in axial alignment with said spindle, whereby relative rotation of said element in a direction to cause linear movement of said element toward said spindle is effective to cause linear displacement of said spindle and rotation thereof relatively to said head.

3. In an adjustable head for a golf club, the combination of a head having a threaded cavity therein, a hosel having an integral extension forming a spindle threadedly engaging a portion of said cavity, said spindle being rotatable relatively to said head in response to an axial component of force applied thereto, and an element threadedly engaging said cavity in axial alignment with said spindle and longitudinally movable in said cavity for applying an axial com-

ponent of force to said spindle, whereby said head is caused to rotate relatively to said spindle.

4. In an adjustable head for a golf club, the combination of a head having a threaded cavity therein, one portion of said cavity having threads of greater lead than the threads in another portion of said cavity, a hosel having an integral extension forming a spindle threadedly engaging said first named portion of said cavity, said spindle being rotatable relatively to said head in response to an axial component of force applied thereto, an adjusting element threadedly engaging said second-named portion of said cavity in abutment with said spindle, whereby linear movement of said adjusting element in the direction of said spindle causes linear displacement of said spindle and proportional rotation thereof relatively to said head, and locking means carried by said head for selectively locking said spindle against counter rotation relatively to said head.

5. A combination, as defined in claim 4, in which the helix angle of the threads on said spindle is greater than 10 degrees.

6. A combination, as defined in claim 4, in which said locking means comprise a plurality of circumferential flats on said spindle and a screw extending through said head into releasable engagement with said flats.

7. In an adjustable head for a golf club, the combination of a head having a threaded cavity therein, a spindle threadedly engaging a portion of said cavity, said spindle being rotatable relatively to said head in response to an axial force applied thereto, an element threadedly engaging said cavity in axial abutment with said spindle for applying an axial force to said spindle, and a member rotatably secured to said head and slidably connected to said element in axial alignment therewith, said member being longitudinally immovable relatively to said head.

JOSEPH VERDERBER.
